UNITED STATES PATENT OFFICE.

ELBRIDGE H. PURDY, OF CINCINNATI, OHIO.

CAR-BRAKE.

SPECIFICATION forming part of Letters Patent No. 381,084, dated April 10, 1888.

Application filed October 20, 1887. Serial No. 252,908. (No model.)

To all whom it may concern:

Be it known that I, ELBRIDGE H. PURDY, of Cincinnati, Hamilton county, Ohio, have invented a new and useful Improvement in 5 Car-Brakes, of which the following is a specification.

While capable of application to street and railway cars generally, my invention has been especially designed and is here shown adapted 10 for use upon cars employed upon the ordinary city and suburban cable tramway.

It consists, essentially, of a pair of jaws so coupled to each other, and one of them so connected to a lever or hand-wheel under control 15 of the carman, and the two jaws having such relation to the slot-flanges, that they are capable of gripping the said flanges with force sufficient to stop the car.

In the accompanying drawings, Figure I is 20 a vertical section of a cable car having one of my brakes represented in its normal or inactive condition. Fig. II represents the same brake in action. Fig. III is a plan showing portions of truck-frame and platform. Fig. 25 IV is a perspective view of the brake proper. Fig. V is a section at the line *v v*. Fig. VI is a side elevation showing certain details of the ratchet mechanism.

1 may represent the track-rails, and 2 the slot-flanges, of a cable tramway.

3 and 3' may respectively represent portions 30 of the truck-frame and platform, 4 one of the truck-wheels, and 5 and 6 the housing and hand-wheel, respectively, of a cable car grip mechanism.

6' may represent the grip ratchet-wheel, 6" its retaining-pawl, and 6'" the releasing-pedal with its retracting-spring 6^{IV}.

My improved car-brake is constructed as 40 follows: A hanger, 7, permanently attached to and extending downward from the truck-frame 3, affords journal-bearing for the upper jaw, 8, of my brake proper. The operating-surface 8' of this jaw is slightly eccentric to 45 its pivots or journals 8". The contour of the said jaw is further such as to keep its under surface parallel to and slightly elevated above the crowns of the slot-flanges 2 in the normal condition of the apparatus. (See Fig. I.) A 50 spur, 9, that extends upward and rearward

from said jaw 8, receives one end of a steel cable, 10, whose other end is secured to the stem 11 of a hand-wheel, 12, in convenient position for manipulation by the carman. A ratchet-wheel, 13, upon the stem 11, and a corresponding pawl, 14, pivoted to the platform, enable the brake to be held to any desired tension.

16 represents the under jaw of the brake proper. The said under jaw is so suspended 60 from the said upper jaw by a link, 17, as in the normal condition of the apparatus to hang beneath and just out of contact with the under side of the slot-flanges 2, (see Fig. I,) and so as, when the device is brought into action, as 65 shown in Fig. II, to coact with the said upper jaw, 8, in tightly gripping the slot-flanges 2.

The brake-operating hand-wheel may be located at a distance from the ordinary grip-wheel, and its stem may consist of a simple 70 rod; but its stem 11 is preferably tubular, as shown, and sleeved around the grip-stem 15; or the said brake may be operated by a lever engaging in a retaining segment-rack similar to the reversing-lever and segment-rack of a 75 locomotive.

I claim as new and of my invention—

1. In a car-brake, the combination, with the slot-flanges of a cable-conduit, of a pair of linked grip-jaws, 8 16, connected by cable 10, 80 with hand-wheel 11 12, ratchet-wheel 13, and pawl 14, as and for the purpose set forth.

2. In combination with the brake proper, 8 16 17, the cable 10, and the grip-operating stem 15, the tubular hand-wheel stem 11, sleeved 85 around said grip-operating stem, as set forth.

3. The combination of brake proper, 8 16 17, the cable 10, the tubular hand-wheel stem 11, and the grip-operating stem 15, within said tubular stem and terminating in ratchet-wheel 90 6', having the retaining-pawl 6", the releasing-pedal 6'", and the retracting-spring 6^{IV}, as set forth.

In testimony of which invention I hereunto set my hand.

ELBRIDGE H. PURDY.
